REMOTE CONTROL SYSTEM

Rodney G. Richardson and John I. Bellamy, Chicago, Ill., assignors, by mesne assignments, to Associated Electric Laboratories, Inc., Chicago, Ill., a corporation of Delaware

Application March 30, 1923, Serial No. 628,723

12 Claims. (Cl. 177—353)

The present invention relates to remote control systems in general, but more particularly to such remote control systems as are suitable for use in connection with remotely controlled electric substations; and as regards some of its features, may be considered an improvement on the co-pending application of Nelson, filed November 16, 1921, Serial No. 515,664, Patent No. 1,765,538, dated June 24, 1930.

10 The broad general object of this invention is the provision of suitable circuit arrangements for use in such a remote control system whereby the chances for error are reduced to a minimum.

15 Specifically, one object of the invention is to produce circuit arrangements such that the despatcher who operates the distant apparatus by means of the remote control system is enabled to check the position or setting of the distant controlling switch before the operation he is about 20 to bring about takes place; and such that the despatcher can restore the distant control switch to normal without operating the device corresponding to the setting of said control switch, in case he discovers by means of the above mentioned checking arrangements that the distant control switch is set in some position other than 25 that in which he intended to set it.

Another object is to produce suitable circuit 30 combinations whereby the despatcher is enabled to check the position of any piece of apparatus at the substation either as a matter of routine or in case he suspects that the usual lamp indication is incorrect.

35 The other objects, which have to do mainly with the detailed circuit arrangements, will appear from time to time, and will be apparent as the specification is further perused.

Referring now to the drawings comprising Figs. 40 1, 2, and 3, the apparatus shown in Fig. 1 is located in the despatcher's office and is connected to the apparatus in the substation by means of the two pairs of conductors 41 and 48, and 49 and 50, respectively. The apparatus shown in 45 Figs. 2 and 3 is located in the substation.

Figure 1 shows the calling device CD by means 50 of which the despatcher operates the control switch in the distant substation. This drawing shows also the switch D which is controlled from the substation and which effects the lighting and extinguishing of the associated signal lamps such as L' and L².

Figure 2 shows the control switch E, located in 55 the substation, which is operated by the calling device CD, Fig. 1, over the conductors 41 and 48. This drawing shows the motor generator MG which is controlled by the starter S and which supplies current to the bus-bar 260 through the circuit breaker CB.

60 Figure 3 shows four relay sets, such as the one

comprising relays 301, 302, and 303, of which two are provided for each starter, circuit breaker, etc. in the substation. These relays control the operation of the switch, D, Fig. 1, through the medium of the relay group RG and the counting switch CS.

The substation shown is assumed to be provided for the purpose of transforming three-phase alternating current energy which is supplied over conductors 215—217, inclusive, Fig. 2, into direct current energy which is supplied to the bus-bar 260. The motor of the motor generator MG is operated in the well-known manner by the three-phase alternating current and the associated 15 generator supplies the direct current.

The motor generator MG may be placed in service by operating the starter S so as to bring the unit up to running speed, and then closing the circuit breaker CB which connects the generator to the bus-bar 260.

The signal operating switch D, Fig. 1, and the controlling switch E, Fig. 2, are mechanically identical with each other, and are of a type of automatic switch disclosed in Automatic Telephony, second edition, a book published by McGraw-Hill Book Company, 370 Seventh Avenue, New York, N. Y. A photograph of this type of switch is shown on page 53 of this publication and a skeleton drawing is shown on page 58. A 30 description accompanies the photograph and describes how this type of switch, which is a switch having a step by step vertical movement and a step by step rotary movement, operates. The circuits of the switches D and E are shown complete 35 and will be described fully hereinafter.

The calling device CD, Fig. 1, may be of any one of several well-known types, but for the purpose of illustration, is assumed to be of the type shown on pages 40 and 41 of Automatic 40 Telephony above referred to. The function of this calling device, as stated hereinbefore, is to control the switch E in the substation over the conductors 41 and 48.

The various pieces of switching apparatus in 45 the substation, such as the starter S and the circuit breaker CB which are shown, may be operated at the will of the despatcher through the medium of the controlling switch E. This operation is effected through the contacts in the 50 bank of wiper 86, as will be explained herein-after.

The starter S is arranged as usual to be returned to normal in case the alternating current supply fails, and the circuit breaker CB is adapted to be thrown out automatically in case the load on the generator of the motor generator unit MG becomes too great.

In order that the despatcher may be kept informed at all times of the respective positions of 60

the various pieces of switching apparatus, each piece of switching apparatus controls the supply of ground potential to two conductors, such as the conductors 118 and 119 associated with the starter S, and 120 and 121 associated with the circuit breaker CB. It will be noted that one of the associated conductors is grounded in case the starter, or circuit breaker as the case may be, is at normal while the other conductor is grounded in case it is operated. It is over these conductors 118-121, inclusive, that the various so-called call sending relay sets, such as the one comprising relays 301-303, inclusive, are controlled. Each time the ground connection is shifted from one of the above mentioned conductors to the other, the call sending relays associated with the newly grounded conductor operate and cause, through the medium of the calling sending relay group RG and the counting switch CS, the signal operating switch D in the despatcher's office to be set into a position corresponding to the new position of the operated device in the substation. This results in one of the despatcher's lamps becoming extinguished and another becoming lighted to give to the despatcher the correct indication.

The counting switch CS, Fig. 3, comprises two semi-circular rows of contacts which are wiped over by the wipers 178 and 179 under the control of the stepping magnet 176. The stepping magnet 176 operates the wipers 178 and 179 by rotating the common spindle to which the two wipers are rigidly secured. These wipers are operated step by step as the magnet is alternately energized and deenergized, being advanced upon the deenergization of stepping magnet 176 rather than upon the energization. One mechanical embodiment of such a switch is shown on page 51 of Automatic Telephony hereinbefore referred to.

It is to be understood that while several batteries are indicated in each of the drawings, there is no need of having more than one battery in the substation and one battery in the despatcher's office, the several batteries being shown for the sake of simplicity.

Although the starter S and the circuit breaker CB, Fig. 2, are the only pieces of substation switching equipment shown, it will be understood that in actual practice a great many more similar devices will be found in each substation. In view of the fact that substations and their equipment are well known, no attempt has been made to show the substation layout in any great detail, only so much being shown as will be needed to describe and explain the various features of the present invention.

It has been assumed that there are several other units of switching apparatus in the substation, which may or may not be similar to the starter S and the circuit breaker CB. It is assumed further that each switching unit has its own call sending relays such as the relays shown in the upper part of Fig. 3, which relays, as before stated, are associated with the starter S and the circuit breaker CB. It is assumed that some of these other sets of relays have contacts connected in series in the two chain circuits extending through the contacts of the relays shown and being connected in the dotted portions of these circuits. It is assumed also that the remaining ones of the other relays are located to the right of the relays shown in the upper part of Fig. 3 as indicated by the arrowheads placed on

the ends of the conductors terminated at the right-hand edge of the drawing.

The apparatus, having been described in general, will now be described in connection with a detailed description of its operation. For this purpose, it will be assumed that the despatcher decides to put the motor generator MG into operation. In order to do so, the first thing the despatcher must do is to effect the operation of the starter S. Accordingly, the despatcher operates the key K associated with the calling device CD, thereby closing a circuit for the slow to pull up relay 16. This relay is made slow to pull up by placing the copper collar on the armature end of the core rather than on the opposite end of the core. This is denoted in the drawings by the position of the copper collar on the upper end of relay 16, which is assumed to be the armature end. Relay 16, therefore, does not operate its armature immediately. Relay 17, which is a slow-acting relay also, energizes immediately, however, owing to the fact that its copper collar is on the end of the core away from the armature. Upon energizing, relay 17 opens a point in the circuit of the lower winding of relay 24 at armature 21 and at armature 20 closes a bridge across the conductors 47 and 48 and including the contacts 14 of the calling device CD.

Before the effect produced by the closing of this bridge across the conductors 47 and 48 is considered, the description of the operation of relays 16 and 17 will be completed. Relay 16 energizes a moment after the energization of relay 17; opens the circuit of relay 17 at armature 18; closes a point in the circuit of the lower winding of relay 24 at armature 19; and at armature 18 places a shunt around armature 20 and its working contact. A moment later, slow-acting relay 17 deenergizes; opens the previously closed point in the bridge across conductors 47 and 48, leaving said bridge closed through armature 18 and its working contact; and at armature 21 completes a circuit for the lower winding of relay 24 including the normally closed contacts controlled by armature 39' of relay 28 and armature 19 and its working contact of relay 16. Relay 24 energizes over this circuit and prepares a locking circuit for itself at armature 31; disconnects wiper 23 and connects up wiper 22 at armature 32; opens a point in the circuit of the signal relay 10 at armature 30'; and at armature 30 shifts the wiper circuit from the local locking conductor to the flasher F. The net result of the energization of relay 24 is that the circuits of the switch D are shifted so that the said switch D will operate correctly as a checking switch when the despatcher operates the substation switch E as will be explained subsequently. It is necessary to make this circuit change at this time owing to the fact that the switch D is normally connected in such a way that when it is operated one of the lamps of a set is extinguished and another lighted as fully explained later.

The energization of relay 24 was delayed as pointed out above in order to permit any call which may have started in the substation, but which has not reached the stage at which relay 28 of the switch D has energized, to be completed before the energization of relay 24 takes place. The above mentioned delay while only momentary is long enough to assure that any call which is already started will have time to proceed far enough to operate the release relay 28 of the

switch D, while other calls are prevented from starting after the closure of the bridge across conductors 47 and 48 as will be explained fully hereinafter.

5 In the substation line relay 60 of the switch E energizes in response to the above mentioned closure of the bridge across conductors 47 and 48 in the despatcher's office and closes a circuit for release relay 61. Relay 61 thereupon energizes 10 and removes the ground from conductor 124 at armature 68. This results in ground being removed from the chain circuit passing through armature 306 and its resting contact of relay 302 and the corresponding armatures on the following 15 relays. This has the effect of preventing any more calls from starting until conductor 124 is again grounded. The way in which this operates to prevent calls from being started will be appreciated perhaps more fully as the description progresses.

As a further result of the energization of relay 61, it prepares a circuit for the lower winding of switching relay 64 at armature 67, and at armature 69 opens a point in the circuit of release magnet 81 and prepares a circuit for vertical magnet 80.

Having operated the key K, as above pointed out, the despatcher now manipulates the calling device CD in accordance with the first digit in the number assigned for operating the starter S. It will be assumed that this number is 11 and, accordingly, the calling device is turned for the digit 1 and produces one interruption in the bridge across conductors 47 and 48. When this occurs, the line relay 60 of the switch E deenergizes once momentarily, thereby sending an impulse of current to vertical magnet 80 over the following circuit: From ground by way of armature 66 and its resting contact, armature 69 and its working contact, contact of off normal spring 84 and said spring, slow-acting series relay 62, and vertical magnet 80 to battery. By the operation of vertical magnet 80, the switch shaft is raised one step and brings the wipers 85 and 86 opposite the first level of bank contacts. Relay 62 is energized in series with vertical magnet 80 and is made slow-acting so as to retain its armature attracted and maintain its own circuit and that of vertical magnet 80 intact after the off normal springs have shifted as they do on the first vertical step. The last part of the impulse sent to vertical magnet 80, therefore, traverses the normally open contacts controlled by off normal spring 84, and armature 70 and its working contact instead of the contact of off normal spring 84 and said spring. In cases when it is desired to raise the shaft of the switch E to some other level, a greater number of impulses are sent and all of them after the first are transmitted over the same path as the last part of the first impulse.

Soon after the termination of the above mentioned impulse to vertical magnet 80, slow-acting series relay 62 deenergizes and transfers the operating circuit from the vertical to the rotary magnet.

When the despatcher manipulates the dial of the calling device CD in accordance with the second digit in the desired number, one interruption is again produced in the circuit of line relay 60, whereupon said line relay 60 deenergizes and sends an impulse of current to the rotary magnet 82 over the following circuit: From ground by way of armature 66 and its resting contact,

5 armature 68 and its working contact, normally open contacts controlled by off normal spring 84, armature 70 and its resting contact, armature 78 and its resting contact, and rotary magnet 82 to battery. Upon receiving this impulse, rotary magnet 82 energizes and steps the switch wipers 85 and 86 into engagement with the bank contacts 87 and 88, respectively, which are the first set of bank contacts in the selected level. Relay 63 is energized in multiple with rotary magnet 82 and maintains the circuit of the lower winding of switching relay 64 open until the switch wipers have come to rest on the selected contacts. Relay 63 is made slow-acting so that it will retain its armature attracted between successive 15 impulses when the number of rotary steps taken exceeds one. Shortly after the termination of the rotary movement, relay 63 deenergizes, thereby connecting up the lower winding of relay 64 at armature 72. When this occurs, relay 64 and 20 relay 303, Fig. 3, energizes in series over the following circuit: From ground by way of armature 159 of relay 141 in the relay group RG, Fig. 3, and its resting contact, armature 147 and its resting contact, conductor 123, armature 67 25 and its working contact, resting contact of armature 72 and said armature, lower winding of switching relay 64, normally closed contacts controlled by armature 76, wiper 85, bank contact 87, conductor 110, resting contact of armature 30 304 of relay 301 and said armature, and relay 303 to battery. Relay 64 of the switch E and relay 303 energize in series over the above traced circuit. Due to its adjustment relay 64 energizes first and closes a locking circuit for its upper 35 winding at armature 75, which locking circuit includes the working contact of armature 68 and said armature; disconnects rotary magnet 82 at armature 78; prepares a circuit for relay 65 at armature 71; places ground on conductor 122 at 40 armature 74, thereby preparing a circuit for relay 135 of the relay group RG which will be closed subsequently; and at armature 76 short circuits and then opens its own lower winding, thereby applying direct ground to wiper 85. 45

Relay 303, Fig. 3, upon energizing over the above traced circuit, closes a locking circuit for itself at armature 307 which includes the normally closed contacts controlled by armature 164 of relay 143 in the relay group RG. As a further result of the energization of relay 303, it connects the first impulse stop conductor 181 to the first digit and second digit stop conductors 128 and 127 at armatures 309 and 310, respectively, thereby preparing the circuits for sending 55 in the number 11 to the despatcher; prepares a circuit for relay 301 at armature 308; and at armature 311 places ground on conductor 126, thereby closing a circuit for relays 149 and 141 in multiple. Relays 140 and 141 energize, but 60 the energization of relay 141 does not have any particular function at this time. Relay 140, upon energizing, places ground on conductor 129, thereby completing the circuit of relay 301 by way of the working contact of armature 308 and 65 said armature. Relay 301 thereupon energizes but does not have any particular function at this time. As a further result of the ground potential being placed on conductor 126 in response to the energization of relay 303, a circuit is closed 70 by way of armature 154 and its resting contact for relay 142. Relay 142, upon energizing, closes a bridge across conductors 49 and 50 at armature 162 including armatures 165 and 167 and their resting contacts in multiple; places ground on 75

armature 164 at armature 160; and at armature 161 closes a circuit for relay 143. Relay 143, upon energizing, places a multiple ground on conductor 126 at armature 163, and at armature 164 shifts the locking circuit of relay 303 so as to include the working contact of armature 164 and said armature and armature 160 and its working contact instead of the normally closed contacts controlled by armature 164. This is done so as to permit a release of relay 303 at the proper time, as will be explained subsequently.

In the despatcher's office line relay 29 of the switch D energizes in response to the closure of the above mentioned bridge across conductors 15 49 and 50 in the relay group RG, and closes a circuit for release relay 28 at armature 41. Upon energizing, release relay 28 opens a point in the circuit of release magnet 44 and prepares a circuit for vertical magnet 47 at armature 48; connects the flasher F to wiper 22 at armature 38; and at armature 39 closes a locking circuit for the upper winding of relay 24 by way of armature 31 and its working contact and opens the circuit of the lower winding of the said relay 24. 20 The switch D is now in readiness to be operated under the control of the sending equipment in the substation.

Returning now to the relay group RG, as a still further result of the ground potential being placed on conductor 126 as described hereinbefore, a circuit is completed for the sending relay 144 by way of the armature 154 and its resting contact, resting contact of armature 169 and said armature, sending relay 144, and the constantly rotating interrupter I to battery. Sending relay 144 now starts to vibrate under the control of the interrupter I. Upon the first effective energization of relay 144, a circuit is completed for stepping magnet 176 of the counting switch CS 30 at armature 166, whereupon said magnet 176 energizes and attracts the armature 177, thereby causing the associated pawl to engage another notch in the wiper driving ratchet wheel. Upon the next deenergization of relay 144, stepping magnet 176 deenergizes also on account of its circuit being opened at armature 166, and upon armature 177 being retracted the wipers 178 and 179 are advanced into engagement with the first set of their bank contacts. When wiper 178 40 comes into engagement with its first associated bank contact, it closes a circuit for pick-up relay 145. Pick-up relay 145 thereupon energizes and removes a shunt from around the armature 165 of relay 144 and its resting contact at armature 167 so as to render each of the subsequent energizations of relay 144 effective in interrupting the bridge across conductors 49 and 50. 50

Upon the next energization of relay 144, the bridge across conductors 49 and 50 is opened at armature 165 and stepping magnet 176 of the counting switch CS is energized again. Upon the subsequent deenergization of sending relay 144, the bridge across conductors 49 and 50 is again closed and the circuit of stepping magnet 176 60 is opened, whereupon the wipers 178 and 179 are advanced into engagement with the second set of associated bank contacts. Since the number to be called is 11 and the first digit of that number is 1, it is now necessary to terminate the first digit. That being the case, the first impulse stop conductor 181 is connected to the first digit stop conductor 128 through armature 309 and its working contact, and ground is accordingly extended to the second contact in the bank of wiper 179, thereby energizing stop relay 70 75

146. Upon energizing, stop relay 146 opens the circuit of sending relay 144 at armature 169; closes a locking circuit for itself at armature 170; and at armature 171 connects stepping magnet 176 to wiper 178 through interrupter contacts 5 175. Stepping magnet 176 accordingly operates in a buzzer-like manner and rotates the wipers 178 and 180 step by step until they pass off the last set of bank contacts, thereby opening the circuit of stepping magnet 176 and the circuit 10 of the slow-acting relay 145. Relay 145, being slow-acting, does not deenergize immediately.

Counting relay 136 is energized in multiple with slow-acting relay 146 through armature 156 and its resting contact and armature 152 and its 15 resting contact. Upon energizing, counting relay 136 closes a locking circuit for itself through counting relay 137 at armature 150. This locking circuit does not become effective, however, until the initial circuit is broken and relay 137 20 is not energized at this time owing to the fact that it is grounded at both terminals.

Upon deenergizing after an interval, slow-acting relay 145 replaces the shunt around armature 165 and its resting contact of sending relay 144 at armature 167 and at armature 168 opens the locking circuit of stop relay 146 and also the initial circuit of counting relay 136. When this occurs, the locking circuit of counting relay 136 through counting relay 137 becomes effective 30 and relay 137 energizes in series with relay 136; opens a still further point in the initial circuit of relay 136 and prepares a circuit for counting relay 138 at armature 152; and at armature 151 disconnects ground from the first digit stop conductor 128 and places ground on the second digit stop conductor 127. 35

Upon deenergizing, relay 146 opens a still further point in its locking circuit at armature 170; disconnects stepping magnet 176 from wiper 178 40 at armature 171; and at armature 169 again connects up sending relay 144.

Relays 144 and 146 and the counting switch CS now repeat the above described operations with the result that the second digit 1 is sent 45 out in the same manner as the first digit 1 except that the stop relay 146 is energized in the second case from the second digit stop conductor 127 and through the working contact of armature 151 instead of from the first digit stop conductor 128 as in the first case. 50

Upon the circuit being closed for stop relay 146 the second time, relay 146 energizes with the hereinbefore described results, and also a circuit is closed for counting relay 138 in multiple with 55 relay 146 and in series with armature 156 and its resting contact and armature 152 and its working contact. Upon energizing, relay 138 closes a locking circuit for itself through counting relay 139, which locking circuit does not become effective until the initial circuit of relay 138 is opened. When the initial circuit of counting relay 138 and the circuit of relay 146 are opened upon the deenergization of relay 145 after the termination of the second digit 1, the locking 60 circuit for relay 138 through the counting relay 139 becomes effective and counting relay 139, upon energizing, opens the circuit of relays 142 and 144 at armature 154; opens another point in the initial circuit of relay 138 at armature 156; 70 and at armature 155 closes a circuit for relay 135 as follows: From ground by way of the working contact of armature 74 of the switch E and said armature, resting contact of armature 71 and said armature, conductor 122, armature 155 75

and its working contact, and relay 135 to battery. Upon energizing, relay 135 closes a locking circuit for itself at armature 148; disconnects conductor 123 from the resting contact of armature 159 of relay 141 at armature 147; and at armature 149 places a multiple bridge across conductors 49 and 50 so as to hold up the switch D in the despatcher's office for a purpose to be explained hereinafter.

10 As the result of the circuit of slow-acting relay 142 being opened, this relay deenergizes after an interval and opens the initial bridge across conductors 49 and 50 at armature 162, leaving said bridge closed by relay 135; opens the circuit 15 of slow-acting relay 143 at armature 161; and at armature 160 opens the locking circuit of relay 303. Relay 143, being slow-acting, remains energized for an interval after its circuit is opened, and maintains the locking circuit of relay 303 20 open at the normally closed contacts controlled by armature 164 long enough to permit relay 303 to deenergize. Upon deenergizing, relay 303 opens a further point in its locking circuit and closes a point in the chain circuit at armature 25 307; removes ground from conductor 126 at armature 311, leaving said conductor grounded at armature 163 of relay 143; and at armature 308 opens the circuit of relay 301. Relay 301, upon deenergizing, prepares a circuit for relay 302 at armature 305, and at armature 304 closes a point 30 in the initial energizing circuit of relay 303 through wiper 85 of the switch E. This circuit is not completed and relay 303 does not energize again at this time owing to the fact that ground 35 has been removed from conductor 123 at armature 159 of relay 141 as explained hereinbefore, thereby removing ground from wiper 85.

After an interval slow-acting relay 143 deenergizes, thereby replacing ground on conductor 125 40 at the normally closed contacts controlled by armature 164 and removing ground from conductor 126 at armature 163, whereupon relays 136-141, inclusive, deenergize, leaving the relays in the relay group RG all deenergized with the exception 45 of the holding relay 135 which is locked up through armature 148 and its working contact from ground placed on conductor 122 at the switch E.

The operation of the switch D in the despatcher's office in response to the calling of the number 11 by the call sending equipment in the substation as described above will now be taken up. When line relay 29 deenergizes in response to the first interruption representing the first digit 55 1 in the number, it closes a circuit for vertical magnet 47 by way of armature 40 and its working contact, contact of off normal spring 46 and said spring, and series relay 27. Vertical magnet 47 operates in the same manner as the vertical magnet 80 of the switch E as explained before and raises the switch shaft one step, carrying the switch wipers 22 and 23 opposite the first level of bank contacts. Slow-acting series relay 27 60 is energized in series with vertical magnet 47 and 65 performs the same function as series relay 62 of the selector E hereinbefore described. After the termination of the impulse sent to the vertical magnet, series relay 27 deenergizes and transfers the operating circuit to the rotary magnet 42.

70 In response to the interruption in its circuit representing the second digit 1 in the number 11, relay 29 deenergizes and sends an impulse of current to rotary magnet 42 by way of armature 40 and its working contact, normally open contacts controlled by off normal spring 46, armature

38 and its resting contact, and armature 36 and its resting contact. Rotary magnet 42 responds to this impulse of current by stepping the switch wipers 22 and 23 into engagement with the first set of bank contacts 8 and 9 in the first level. 5 Slow-acting relay 26 is energized in multiple with rotary magnet 42 and maintains the switch wiper disconnected during the rotary movement. Upon deenergizing, at the termination of the rotary movement, slow-acting relay 26 connects up 10 wiper 22 at armature 31', thereby completing a circuit for the lamp L² traceable from ground through the flasher F, spring 30 and its working contact, springs 39, 37', lower winding of relay 25, through the normally closed contacts controlled by springs 35, spring 32 and its make contact, wiper 22 and contact 8, through the lamp L² to grounded battery. The lamp L² accordingly starts flashing so as to attract the attention of the despatcher and inform him that 15 that is the lamp corresponding to the set position of the switch E in the substation. The rotary magnet cut-off relay 25 energizes in series with the lamp L²; shorts its lower winding at armature 35; locks itself at armature 34 over a circuit including the upper winding of relay 25, armature 34 and its make contact, armature 39' and its make contact to ground; and at armature 36 disconnects rotary magnet 42 and relay 26 20 from the operating circuit so as to prevent their unnecessary operation during the subsequent release of the switch D.

In order to facilitate the explanation, it will be assumed for the time being that due to an error by the despatcher in operating his calling device CD or due to a false operation of the switch E, Fig. 2, the said switch E landed upon a set of contacts other than the first set in the first level as assumed hereinbefore. That being the case the call sending mechanism at the substation fails to operate the switch D or else causes the switch D to be set on a set of contacts other than the ones with which the lamp L² is associated. Whether the call sending mechanism responds or not depends upon whether the conductor associated with the contact on which the wiper 85 of the switch E actually lands is connected through to the associated call sending relay such as 303 for example (see conductor 110) or is disconnected by the associated cut-off relay such as 301 for example (see conductor 111). In this case no lamp is flashed or else the wrong lamp is flashed, and in either case the despatcher is informed that the substation switch is not on the desired set of contacts.

Assuming at any rate that the desired lamp does not start flashing, the despatcher releases the switch E at this stage without operating the device for which it is set. In order to do this, he merely releases the key K which he has been holding operated during this time, thereby opening the circuit of relay 16 and permitting it to deenergize. Upon deenergizing, relay 16 opens the bridge across conductors 47 and 48, whereupon line relay 60 of the switch E deenergizes and sends an impulse of current over the previously traced operating circuit to the relay 63. Relay 63, upon energizing at this time, opens the locking circuit of holding relay 135 in the relay group RG at armature 71, whereupon relay 135 deenergizes and 65 opens the bridge across conductors 49 and 50, permitting the switch D to release in a manner to be described subsequently. A moment after the deenergization of line relay 60, slow-acting release relay 61 deenergizes due to the prolonged opening 70 75

of its circuit, thereby bringing about the release of the switch E in a manner to be described subsequently.

Returning now to the original assumption that the switch E operated as the despatcher desired and that the switch D was set on the contacts 8 and 9 with the result that the lamp L² started flashing, the despatcher, upon noting that the desired lamp is flashing, knows that the switch E is set in the desired position and not in some other position. The despatcher now operates his calling device CD in accordance with any desired digit, the digit 1, for example, thereby producing a momentary interruption in the circuit of line relay 60 of the switch E, whereupon the line relay 60 deenergizes momentarily and sends an impulse of current to slow-acting relay 63, resulting in the energization of said relay 63. Relay 63, being slow-acting, maintains its armature attracted for an interval after the termination of this impulse and at armature 71 opens the locking circuit of holding relay 135, Fig. 3, whereupon relay 135 deenergizes and opens the bridge across conductors 49 and 50. As a further result of the energization of relay 63 of the switch E, it prepares a circuit for relay 65 at armature 73. When line relay 60 energizes again after its momentary deenergization, it completes a circuit for relay 65 as follows: From ground by way of armature 66 and its working contact, working contact of armature 73 and said armature, working contact of armature 71 and said armature, and relay 65 to battery. Upon energizing, relay 65 places ground on wiper 86 at armature 79 in order to operate the starter S.

After having manipulated his calling device for the digit 1 to initiate the operation of the starter S as described above, the despatcher releases the key K, thereby opening the circuit of relay 16. It may be pointed out that the off normal spring 15 comes into engagement with its associated contact as soon as the dial of the calling device is turned off normal, thereby closing a circuit for relay 16 independent of the key K so as to maintain the relay 16 energized a sufficient length of time in case the despatcher happens to release the key K too quickly while the calling device is returning to normal after having been operated the last time. Upon deenergizing, relay 16 opens the bridge across conductors 47 and 48 at armature 18, whereupon the line and release relays of the switch E deenergize one after the other, and release relay 61, upon deenergizing, opens the operating circuit and closes the release magnet circuit at armature 69, and at armature 68 removes ground from the locking armature 75 of relay 64 and replaces ground on the chain conductor 124. Relay 65 deenergizes in response to the falling back of armature 66 of line relay 60 and removes ground from wiper 86 and relay 64 deenergizes in response to the opening of its locking circuit by release relay 61. Release magnet 81 energizes in response to the deenergization of release relay 61 and is energized over the following circuit: From ground by way of armature 66 and its resting contact, armature 69 and its resting contact, off normal contacts 83, and release magnet 81 to battery. Upon the energization of release magnet 81, the shaft and wipers of the switch E are restored to normal position, and the circuit of release magnet 81 is opened at off normal contacts 83 by the switch shaft when the latter reaches its normal position.

The line and release relays 29 and 28 of the switch D in the despatcher's office deenergize one after the other in response to the opening of the

bridge across conductors 49 and 50 in the substation as pointed out hereinbefore. In response to the deenergization of release relay 28, armature 39' is retracted and the circuit of relays 24 and 25 is opened, whereupon these relays deenergize. As a further result of the deenergization of release relay 28, the circuit of release magnet 44 is closed at armature 40 and includes off normal contacts 45 which open when the switch shaft reaches normal in response to the resulting energization of release magnet 44. The switches D and E are now in their normal positions and are ready to be used again.

In the substation, relay 241 of the starter S energizes in response to the ground potential 15 being placed upon wiper 86 of the switch E while the same is in engagement with bank contact 88 as explained hereinbefore.

Upon energizing, relay 241 closes a locking circuit for itself at armature 246 in series with the 20 resting contact of armature 232 and said armature; closes a circuit for the solenoid 230 through armature 244 and its resting contact at armature 245; and at armature 247 closes a circuit for relay 240 through the resting contact of armature 242 25 and said armature. Relay 240 does not energize immediately, however, owing to the fact that it is wound so as to be highly inductive and owing also to its stiff adjustment. In response to the closing of the circuit of the solenoid 230, said so- 30 solenoid 230 energizes and attracts the plunger 228, thereby rotating the operating lever in such a direction as to swing all of the pivoted switches 218-223, inclusive, to the left. This results in the three-phase auto-transformer being connected to 35 the three-phase supply leads 215-217, inclusive. The switch levers 221-223, inclusive, connect the three conductors of the three-phase induction motor of the motor generator MG to the reduced potential taps of the auto-transformer. When this occurs, the motor generator MG starts to 40 pick up speed and, as usual, draws a very heavy current for starting. This heavy current is sufficient to operate the relay 238 which is shunted around resistance 224 connected in one of the 45 auto-transformer leads. Relay 238 energizes before the slow to energize relay 240 has had time to energize and opens the circuit of the latter.

When the motor generator MG has picked up sufficient speed to approach synchronism, the intake of current is no longer sufficient to maintain the marginally adjusted relay 238 energized. Accordingly, relay 238 deenergizes and closes the circuit of relay 240 at armature 242. Relay 240, upon energizing after the interval for which it is 50 adjusted, attracts armature 244, thereby opening the circuit of solenoid 230 and closing a circuit through solenoid 231. When this occurs, the plunger 229 is attracted and the operating lever 226 swings the switch arms 218-223, inclusive, to 55 the right, thereby disconnecting the auto-transformer from the line and connecting the three conductors of the motor direct on to the line instead of to the low potential taps. One of the conductors through which current is now supplied to the motor is cut and the resistance 228 is inserted therein. The holding magnet 233 is connected in shunt of resistance 228 through armature 243 and its resting contact. Holding magnet 233 accordingly energizes and attracts 60 its armature 232 which engages the end of the lever 226, thereby holding said lever in its operated position independent of the solenoid 231. The attraction of armature 232 results in the locking circuit of relay 241 being broken. Relay 70 75

241, upon deenergizing, opens the circuit of relay 240 at armature 247, whereupon relay 240 deenergizes and opens the circuit of solenoid 231, leaving the lever 226 under the control of armature 232 which holds said lever 226 in its operated position. The motor generator MG is now up to speed and is ready to carry its portion of the load.

As a further result of the starter S being thrown to running position, ground is removed

10 from conductor 119 and placed on conductor 118. When this occurs, the cut-off relay which is shown locked up over conductor 119 deenergizes and relay 302 is energized over conductor 118 through armature 305 and its resting contact.

15 Upon energizing, relay 302 opens the chain circuit so as to render the energization of any one of the other similar relays ineffective in case it should occur at this time. Relay 302 also closes a circuit for relay 303 at armature 306 as follows:

20 From ground by way of armature 68 and its resting contact, chain conductor 124, armature 158 and its resting contact, armature 306 and its working contact, and relay 303 to battery. Upon energizing, relay 303 opens at armature 307 the

25 chain circuit extending to the other similar relays so as to unlock any of them that might have just become locked up over this chain circuit. These two chain circuits, it may be pointed out, are used in order to secure the desired effect that 30 only one relay, such as 303, can remain energized while a call is being sent in to the despatcher's office. Otherwise, two or more such relays might be energized at the same time and prevent the successful operation of the call sending

35 equipment. As a further result of the energization of relay 303, it closes a locking circuit for itself at armature 307 which includes the locking conductor 125 which is grounded by way of the normally closed contacts controlled by armature

40 164 of relay 143; prepares a circuit for relay 301 at armature 308; connects up the first and second digit stop conductors to the first impulse stop conductor 181 at armatures 309 and 310; and at armature 311 places ground on conductor 126

45 with the hereinbefore described results that relays 140 and 141 are energized. Relay 140, it may be explained at this time, is highly inductive and stiffly adjusted and for these reasons does not energize immediately. Relay 141, however,

50 energizes right away and opens at armature 158 another point in the chain circuit extending through armature 306 and its resting contact and similar armatures and contacts on the corresponding relays in the other sets. This is done

55 to prevent the operation of any relay set from being interfered with by a preceding relay set after the operation has progressed thus far. While this operation has no particular utility at this stage of the operation in this particular case,

60 it is a very necessary operation when the call sending relay set in operation is one of the sets other than the first in the chain. After an interval, the slow to pull up relay 140 energizes and places ground on the common conductor 129, thereby closing a circuit for cut-off relay 301

65 through the working contact of armature 308 and said armature. Relay 301, upon energizing, disconnects conductor 110 from relay 303 at armature 304, and at armature 305 opens the circuit of relay 302 and locks itself to grounded conductor 118 to spring 305 and its make contact. Relay 302, having completed its operation, now deenergizes.

70 It can probably now be understood just why the grounding of the common conductor 129 was

delayed. This delay is necessary in order to give time for any one of the sending relays, corresponding to 303, that might have become energized prior to the energization of relay 303 to fall back, otherwise the associated cut-off relay, corresponding to 301, would have been prematurely operated, thereby cutting off the associated control conductor before the corresponding call is sent to the despatcher's office.

75 As a further result of the placing of ground 10 on conductor 126 by relay 303, relay 142 operates to close a bridge across conductors 49 and 50 at armature 162, and the remaining relays 143-146, inclusive, together with the counting switch CS operate as described hereinbefore to send in the 15 number 11 to the control switch D in the despatcher's office. At this time since the switch E is not operated, the conductor 122 is not grounded and holding relay 135 does not energize after the call has been sent in and the switch 20 D is, therefore, released upon the opening of the bridge across conductors 49 and 50 at armature 162 when relay 142 deenergizes, which it does as described in the preceding example.

25 It will be remembered that, as explained hereinbefore, the slow-acting relay 143 maintains conductor 126 grounded at armature 163 after the ground has been removed from the said conductor 126 at one of the call sending relays, such as relay 303. This is done so as to prevent another call from being sent in to the despatcher's office before the switch D has had time to return to normal. The line circuit of the switch D is opened at armature 162 by relay 142, which relay opens 30 the circuit of slow-acting relay 143 at the same time. Another call cannot be sent in, however, until after the slow-acting relay 141, which is maintained energized over conductor 126, has deenergized and closed the chain circuit at armature 158. This interval is that required for the 35 two slow-acting relays 143 and 141 to fall back one after the other, and is sufficiently long to permit the switch D to be completely restored to normal position.

40 In the despatcher's office, since the despatcher is not making a call, relay 24 is not energized and, consequently, upon the energization of slow-acting relay 26 during the rotary movement of the wipers 22 and 23, a circuit is closed for the pilot 45 relay 10 as follows: From ground by way of the working contact of armature 37 and said armature, armature 30' and its resting contact, and pilot relay 10 to battery. Pilot relay 10, upon energizing, closes a locking circuit for itself at 50 armature 13, and at armatures 11 and 12, closes the circuits for the lamp L and the buzzer B so as to inform the despatcher both visually and audibly that a call is coming in. Also, since relay 24 is not energized, the wiper 23 instead of the 55 wiper 22 is connected up to the lower winding of relay 25, and as soon as the slow-acting relay 26 deenergizes after the switch wipers have been set on the contacts 8 and 9, relays 25 and 2 energize in series over the following circuit: From ground 60 by way of the resting contact of armature 30 and said armature, armature 39 and its working contact, armature 31' and its resting contact, lower winding of switching relay 25, normally closed contacts controlled by armature 35, armature 32 65 and its resting contact, wiper 23, bank contact 9, relay 2, and the associated resistance to battery. Due to its lighter adjustment, relay 25 energizes 70 first over this circuit and closes the previously traced locking circuit for itself at armature 34; 75

disconnects rotary magnet 42 and relay 26 at armature 36; and at armature 35 grounds the wiper 23 over a circuit which is independent of its own lower winding. Relay 2, upon energizing, 5 closes a locking circuit for itself at armature 3, and at armatures 4 and 5 opens the circuit of the lamp L' and closes a circuit for the lamp L² as follows: From ground by way of the flasher F, resting contact of the upper spring of the key 10 K' and said spring, working contact of armature 5 and said armature, armature 4 and its working contact, and the lamp L² to battery. Accordingly, the lamp L² starts flashing under the control of the flasher F. The lamp is made to flash 15 at this time so as to give the despatcher immediate indication of the particular set of lamps in which the change has occurred. This obviates any necessity for a checking operation by the despatcher.

20 The despatcher, after having been informed by the buzzer B and the pilot lamp L that a call is coming in, operates the push button P, thereby opening the locking circuit of the pilot relay 10, whereupon said relay 10 deenergizes and extinguishes the lamp L and disconnects the buzzer B.

After having taken sufficient note of the set of lamps in which the change has occurred, the despatcher operates the locking key K' to its alternate position by pushing the locking push 30 button shown, thereby disconnecting the working contact of armature 5 from ground by way of the flasher F and connecting it to ground direct. This causes the lamp L² to stop flashing and to light steadily. This operation also serves to prepare a flashing circuit for the lamp L' which becomes effective upon the subsequent deenergization of the relay 2.

The switch D is released at this time in the hereinbefore described manner.

40 In order to put the motor generator MG finally into operation, it is necessary that the circuit breaker CB be thrown in. In order to effect this operation, it is necessary for the despatcher to close the bridge across line conductors 47 and 48 and then dial the number assigned to the throwing in of the circuit breaker CB. This number, 45 it will be assumed, is 19. Accordingly, the despatcher operates the key K with the hereinbefore described results and then operates his calling 50 device CD for the two digits 1 and 9 in the number 19.

In response to the operation of the calling device CD in accordance with the digit 1, the wipers of the switch E are raised opposite the first level 55 of bank contacts, and in response to the operation of the calling device CD in accordance with the second digit 9 of the number, the wipers 85 and 86 are brought into engagement with the ninth set of bank contacts in the first level, 60 which are the contacts 91 and 92. When wiper 85 is grounded at the cessation of the rotary movement, ground is placed on bank contact 91 and is extended through conductor 112 to the third set of relays, counting from the left, shown 65 in the upper part of Fig. 3. This results in these relays operating in the same manner as described for relays 301-303, inclusive, and the number 19 is sent in to the substation by the calling sending equipment, thereby bringing the wipers of 70 the switch D in the substation into engagement with the ninth set of bank contacts in the first level. This results in the associated lamp being flashed in the usual manner, thereby giving the despatcher the indication that the switch E is 75 on the right set of bank contacts. It will be noted

that the number 19 is sent out by the call sending equipment in this case instead of the number 11 described in the preceding case, owing to the fact that the ninth impulse stop conductor 189 is used to terminate the second digit rather than the first impulse stop conductor 181.

The despatcher now operates the calling device CD again in order to throw in the circuit breaker CB and, when this occurs, the wiper 86 is grounded momentarily as hereinbefore described, 10 with the result that the ground potential is extended by way of bank contact 92 and conductor 116 to the solenoid 256 of the circuit breaker CB. The momentary energization of solenoid 256 results in the plunger 255 being attracted, where- 15 upon the lever 254 is rotated, thereby connecting the switch arm 253 with the lead extending to the bus-bar 260. The armature 257 of trip magnet 258 is provided with the notch in the upper end in which the end of the lever 254 catches, 20 thereby holding the circuit breaker in its operated position. The lever 254 also ungrounds conductor 121, thereby causing the associated locked up relay to deenergize, and places ground on conductor 120 with the result that the call sending 25 equipment is again operated to send in the number 19 to the switch D in the despatcher's office, which has been released in the hereinbefore described manner in the meantime owing to the de-energization of holding relay 135 which occurred 30 in response to the last mentioned operation of the calling device CD.

The switch E is released in the usual manner when the despatcher releases the key K after having brought about the operation of the circuit breaker CB.

It will be noted that in case the alternating current supply to the motor of the motor generator MG is interrupted, the holding magnet 233 is deenergized, whereupon the armature 232 is re- 40 tracted and the starter returns to its normal position. When this occurs, the ground potential is removed from conductor 118, allowing the locked up relay 301 to deenergize and a ground potential is placed on conductor 119 with the re- 45 sult that the number 12 is sent in by the call sending equipment, which results in the wipers 22 and 23 of the switch D being brought into engagement with the bank contacts 6 and 7 which are the second set of bank contacts in 50 the first level. When this occurs, the wiper 23 places ground on bank contact 7, thereby short circuiting the relay 2 and causing the said relay 2 to deenergize. The switch D is then released automatically in the usual manner. The de- 55 energization of relay 2 results in the lamp L² becoming extinguished and the lamp L' being connected up to the flasher F through the working contact of the lower spring of the associated key K' and said spring, resting contact of armature 5 and said armature, and armature 4 and its resting contact. The despatcher, upon noting the flashing condition of the lamp L' knows that the starter S has returned to normal. The des- 60 patcher causes the lamp L' to light steadily by 65 retracting the plunger of the key K' and allowing the springs thereof to assume their normal position.

The despatcher may in this case take such steps as he may deem necessary, either reoperat- 70 ing the starter S immediately or waiting a sufficient length of time to permit the supply of current to the leads 215-217, inclusive, in the substation to be replaced.

Although it is not shown as such, the cir- 75

cuit breaker CB is preferably of the type having a suitable circuit arrangement for tripping the circuit breaker in case the current is reversed. Assuming the circuit breaker CB to be a reverse current circuit breaker, it is tripped immediately after the starter S is returned to normal, owing to the fact that the motor generator MG slows down and the generator thereof starts to run as a motor, taking current from the bus-bar 260. The circuit breaker CB has not been shown, however, as a reverse current circuit breaker for the reason that such circuit breakers are well known and also for the reason that it was desired to keep the drawings as simple as possible, so that more stress might be laid on the essential points of the invention.

In case the motor generator MG becomes overloaded by current being drawn from the bus-bar 260, the trip magnet 258 which is shunted around the resistance 259 energizes and trips the circuit breaker. This results in ground being removed from conductor 120 and placed on conductor 121. The result of ground being placed on conductor 121 is that the associated relay group is operated and the call sending equipment sends in the number 10 due to the fact that the first and tenth impulse stop conductors 181 and 190, respectively, are associated with this relay group. This causes the switch D in the despatcher's office to operate in the usual manner to give the despatcher the necessary signal.

It has been shown above how either the starter S or the circuit breaker CB can be returned to normal owing to an abnormal condition in the substation. It will now be explained how the despatcher himself can initiate either of these operations. In order to restore the circuit breaker CB, the despatcher dials the number 10, causing the wipers 85 and 86 of the switch E to be brought into engagement with the tenth set of bank contacts in the first level. Then, when the despatcher gives the calling device CD the extra operation after receiving the usual indication that the switch E is on the right contacts, the bank contact 94 is grounded by the wiper 86 and trip magnet 256 of the circuit breaker CB is operated over conductor 117.

Similarly, the starter S can be restored by the despatcher who for this purpose closes the line circuit of the switch E by means of the key K and then dials the number 12, thereby causing the wipers 85 and 86 of the switch E to be set upon the bank contacts 89 and 90. The despatcher then gives the calling device CD a further turn, after having received the usual indication that the switch E is on the desired set of contacts, thereby causing a ground potential to be supplied to bank contact 90 by way of the wiper 86. This ground potential extends by way of conductor 115 to relay 239 in the starter S which thereupon energizes and opens the circuit of holding magnet 233, whereupon the starter S is returned to its normal position, with the result that the corresponding number 12 is sent in to the despatcher's office by the call sending equipment in the manner described above.

In case the despatcher has any reason to believe that the lamp indication of the position of any particular substation switching devices is incorrect, he may verify his opinion or, at any rate, ascertain the true position of any particular switching device such as the starter S, for example, by closing the line circuit of the switch E and dialling either one of the two numbers assigned to that device. In case the lamp L',

Fig. 1, is lighted, indicating that the starter S is at normal, the despatcher may verify this by dialling the number 11, with the result that the lamp L' starts flashing as hereinbefore described in case the starter is actually at normal, while if the lamp L' indicates that the starter is at normal at a time when the starter is actually in its operated position, the despatcher will not be able to receive any response when he dials the number 11 for the reason that cut-off relay 301 10 will be operated at that time and the lead 110 will be disconnected from relay 303 at armature 304.

In this case the despatcher will probably want still further verification in order that he may 15 be absolutely sure of the position of the starter S and he will, therefore, dial the number 12, whereupon the switch E through its wiper 86 places ground on conductor 111 which is not at this time disconnected from the associated relay 20 in Fig. 3, and, as a result, the call sending equipment sends in the number 12 resulting in the flashing of the lamp L'.

It will be seen from the foregoing that the present system is a considerable improvement 25 over prior systems of the same nature in that the despatcher is enabled to ascertain the position of the substation switch before he operates the device associated with that position of the switch. It will be seen further that the despatcher is enabled to check the indicated position of any piece of switching apparatus against the actual position.

What we claim is:

1. In a remote control system, a calling device, 35 a control switch, a control circuit extending between said device and switch, a key associated with said calling device, two relays operated in response to the operation of said key, said relays jointly, completing said control circuit, means 40 for operating said control switch over said control circuit in response to a manipulation of said calling device, and contacts operated by said calling device for maintaining said control circuit completed independent of said key, while 45 said calling device is being operated and for a definite interval thereafter.

2. In a remote control system, a switching device having a plurality of positions, a visual signal for each position of said device, means 50 whereby one of said signals is operated to indicate the position of the switching device, a circuit between said device and signal, means for moving said switching device to a new position, means responsive thereto and controlled over 55 said circuit for restoring said operated signal to its normal condition and for intermittently operating the signal associated with the new position of the switching device, and manually controlled means for causing the last named signal to 60 be operated steadily.

3. In a remote control system, a plurality of switching devices each having a plurality of positions, a set of signals for each device, one signal of the set corresponding to each position 65 of the associated device, automatic means for maintaining the proper signal operated to indicate the position of the device, means responsive to a change in position of the device for intermittently operating the signal indicating 70 the new position and retiring the signal indicating the old position of the device.

4. In a remote control system, a plurality of switching devices each having a plurality of positions, a set of signals for each device, one 75

- controlled by each position of the associated device, means controlled from the main station for extending a circuit to a device to change its position, and automatic means responsive to 5 the extension of said circuit for intermittently operating the signal which indicates the position into which the device is to be moved.
5. In a remote control system, a plurality of switching devices each having a plurality of 10 positions, a set of signals for each device consisting of a signal for each position of the device, automatic means for maintaining the proper signal operated to indicate the position of the device means responsive to a change in 15 position of a device for intermittently operating the signal indicating the new position and retiring the signal indicating the old position, means for selecting a device and moving it from one position to another, means operating in response to said selection to control said automatic means to intermittently operate the signal indicating the new position and to maintain the signal indicating the old position.
6. In a remote control system, a plurality of 20 devices each having a plurality of positions, a set of signals for each device comprising a signal for each position of the device, means for selecting a device to change its position, an automatic switch operated in response to said selection to intermittently operate the signal indicating the position into which the device is to be moved without affecting the operation of the signal which indicates the position in which the device stands, means for then changing the position of the device, means responsive to said change in position to control said automatic switch to intermittently operate the signal indicating the position into which the device moves and to retire the signal indicating its old 25 position.
7. In a remote control system, a plurality of switching devices, signalling devices, means for selecting a device at the substation to change its position, switching mechanism automatically responsive to a change in position of one of the 30 devices to control the signalling means to indicate that change in position, automatic means controlled by the initiation of the operation of said first means to change the function of said switching mechanism to prevent its indication of further changes of the devices on said signalling means and to prepare it to indicate the position of said selecting means, and means for delaying 35 the change in function of said switching mechanism for a certain time after the initiation of the operation of said first means to permit indications of changes already in progress to be completed.
8. In a remote control system, a control circuit and a checking circuit, a step by step control switch, a calling device, a key associated with said calling device, means responsive to the operation of said key for completing said control 40 circuit, means for operating said control switch over said control circuit in response to a manipulation of said calling device, and contacts operated by said calling device for maintaining said control circuit completed independent of said key as long as said dial remains in an operated position, and means responsive to the operation of said control switch for closing said second circuit and for maintaining it closed while said control circuit is closed.
9. In a control system, a control circuit terminating in a selective control switch, a checking circuit terminating in a selective checking switch, a plurality of switching devices, each having a plurality of positions, an indicating device for each of said switching devices, each indicating device having a plurality of positions corresponding to the positions of the corresponding switching device, means for moving each of said switching devices from one position to another, means including checking means controlled by the change of position of a device over said checking circuit and through the medium of said checking switch for causing the associated indicating device to assume a corresponding position, a sender operative over said control circuit for setting said control switch in a desired position preparatory to moving one of said switching devices, means controlled through said positioned control switch for moving said checking switch to a position corresponding to said control switch position, means automatically controlled by the operation of said sender for rendering said checking means ineffective to change the position of said indicating device, and means independent of said indicating means and controlled by said automatically operated means for indicating the set position of said checking switch.
10. In a remote control system, a plurality of switching devices, a set of signals for each device, a selective switch, means operating automatically in response to a change of condition of any device to operate said switch to select the associated set of signals, means in said switch for operating said signals to indicate the change in the condition of the device, another automatic switch, means for operating said second switch to select one of said devices, means operated by said second switch to render said first means unresponsive to changes in the conditions of said devices, and means controlled by the operation of said second switch for operating said first means to operate said first switch in a distinctive manner to indicate the position of said second switch.
11. In a remote control system, a plurality of switching devices each operable from one position to another, signalling means individual to each of said devices, common selecting means for selecting any one of said devices for operation, means for operating said device, means responsive to the selection of said last device for operating said signalling means in one manner to indicate such seizure, said means also responsive to the operation of said device for operating said signalling means in a different manner to indicate the actual operation of said device.
12. In a remote control system, a plurality of switching devices, an operating circuit individual to each of said devices, signalling means individual to each of said devices, means for preparing the operating circuit of one of said devices, means responsive to the preparation of said circuit for operating the signalling means individual to said device in one manner to indicate the said prepared operating circuit, means for completing said operating circuit to operate said device, and said second means reoperated responsive to the actual operation of said device over said circuit for reoperating said signalling means in a different manner to indicate the actual operation of said device.
